UNITED STATES PATENT OFFICE.

WILLIAM OLIVER DALY, OF MOBILE, ALABAMA.

AUXILIARY CAR-STEP.

952,442.

Specification of Letters Patent. Patented Mar. 22, 1910.

Application filed April 20, 1909. Serial No. 490,996.

To all whom it may concern:

Be it known that I, WILLIAM OLIVER DALY, a citizen of the United States, and a resident of Mobile, in the county of Mobile, State of Alabama, have invented certain new and useful Improvements in Auxiliary Car-Steps, of which the following is a specification.

My invention is an improvement in auxiliary car steps, and consists in certain novel constructions and combinations of parts hereinafter described and claimed.

The object of the invention is to provide a step of the kind specified which, when not in use, will be folded neatly and inconspicuously against the bottom of the fixed steps and which may be easily moved into operative position from the platform of the car.

Referring to the drawings forming a part hereof: Figure 1 is a perspective view of a portion of a car provided with the improvement, showing the step in operative position; Fig. 2 is an end view, showing the step folded; Fig. 3 is a transverse section of a portion of the car platform, showing the operating mechanism; Fig. 4 is a partial transverse section of the fixed steps, showing a detail of the folding mechanism; Fig. 5 is a plan view of the locking mechanism; Fig. 6 is a section on the line 6—6 of Fig. 5, looking in the direction of the arrows; and Fig. 7 is a perspective view of one of the step supporting brackets.

The embodiment of the invention shown in the drawings comprises a step 1, preferably of wood, and resting at each end upon a plurality of perforated ears 2 extending from the lower edge of the body portion of a bracket 3, which body portion is provided at approximately its center with a lug 4 extending outwardly and provided with an inclined transverse slot 5, and the ears traversed by bolts or screws for securing the ears to the step. A bar 8 has one of its ends secured in the slot by means of a bolt or lag screw 9, and the bar is slidable in bearings 10 secured to the side plates 11 of the usual car steps, the upper end of the plate having an angular portion 12 for engaging the uppermost bearing to limit the downward movement of the bar with respect to the side plate.

It will be understood that a bar 8 is connected with each end of the auxiliary step, and that the said step corresponds in shape

and dimensions with the other steps, and is finished in like manner.

A plate 13 is secured transversely of the auxiliary step by any suitable means, as, for instance, bolts 13^a, and the inner end of the plate projects beyond the edge of the step and is provided with spaced ears 14. A rod 15 has one of its ends pivoted between the ears, and the other end is provided with spaced ears 16, between which is pivoted the outer end of a rigid arm 17, extending from the center of a rock shaft 18, journaled in arms 19, connected to the side plates 11. Each of the arms 19 is secured to the adjacent plate by screws 20 and one of the arms is formed in two sections, one 20^a of which is of greater thickness than the other and is longitudinally recessed, as at 21, to receive the other, the sections being secured together by screws 22. The outer section 20^a is provided with a split bearing 23, whose sections are secured together by bolts 24.

The purpose of the above construction is to permit the insertion and removal of the rock shaft, the sections of the split bearing 80 being loosened to permit the introduction or removal of the shaft, and the end of the shaft adjacent to the car body 25 is threaded and engaged by a nut 26, while the opposite end is provided with an integral arm or crank 85 27. The arm 27 is provided with spaced ears 28, between which is pivoted one end of a link 29, the link extending upwardly through an opening 30 in the platform 31 of the car, and being provided at its upper end 90 with a pair of spaced ears 32, for a purpose to be presently described.

A lever 33 is pivoted to an ear 34 on a bracket 35, secured to the car body, as at 36, the lever having spaced ears 37, between 95 which is received the ear 33, and adjacent to the point of pivotal connection the lever is provided with an angular portion 38, which is received between the ears 32 of the link and connected therewith by a rivet or bolt 39. The angular portion 38 is formed, in the present instance, by bending the lever at an angle to the body portion, and return bending it at an angle to the first bend, and the free end of the lever is provided with a 100 grip 40 for convenience in manipulating the same.

It will be evident from the description that when the free end of the lever is elevated the rock shaft will be oscillated to 110

swing the arm 17, and through the connection of the rod 15 therewith the auxiliary step will be pushed downwardly and outwardly into the position shown in Fig. 1, the step being guided and limited in its movement by the bar 8.

A means is provided for locking the step in closed position, the said means being arranged upon the platform 31 and engaging the link 29. The said means consists of a plate 41, shown in Figs. 3, 5 and 6 in detail, secured to the platform by screws 42, and the sides of the plate are each provided with a flange 43 overlying the plate. A pair of levers 44 and 45 is pivoted on the plate, as at 46, the lever 45 being pivoted directly thereto by its inner end, while the lever 44 is provided with a lateral lug engaged by the pivot 46. The lever 44 extends beyond the plate at both ends, and the one end 47 is bent at an angle to the lever proper and is provided with a cross head 48. The opposite end of the lever is provided with a recessed jaw 49 for receiving the link, and the free end of the lever 45 is provided with a similar jaw 50, coöperating with the jaw 49. A spring 51 is connected by one end with the lever 44 and by the other with a pin 52 on the plate, and acts to retain the jaws clamped on the link. By moving the end 47 of the lever 44 into the position shown in dotted lines in Fig. 5, the jaws are released from the link, which is then free to move longitudinally. The lever 45 is recessed, as at 53, in order that it may move under the overlying flange, and a strap 54 is arranged across the plate, the ends of the strap being bent at an angle thereto for engaging the outer edges of the sides of the plate. The link 29 is provided with an integral collar 55 which engages the lower faces of the jaws when they are closed, and the engagement of the said parts, rather than the gripping action of the jaws, is relied upon to restrain the movement of the rod upwardly.

It will be evident from the description that, when it is desired to lower the step, the levers may be spread apart by pressing the cross head 48 with the foot, to release the link. The lever 33 is then swung into the position shown in dotted lines in Fig. 3 and in full lines in Fig. 1, thus pushing the step into the position shown in the latter figure. After the step has served its purpose the lever is swung in the reverse direction, which elevates the step into the position shown in Fig. 2, the step fitting neatly against the lowest fixed step, so that it will hardly be noticeable. The side plates 11 of the fixed steps are extended below the lowest fixed step, as at 56, and are recessed, as at 57, to receive the lugs 4, the auxiliary step being received between the said ends when in elevated position.

65 It will be observed from an inspection of

Fig. 3 that the lower face of the collar 55 is beveled, as at 58, while the upper face is flat, so that the beveled face will spread the levers when the link moves downwardly. The jaws permit the link to move freely in a downward direction, but prevent its upward movement.

It will be evident from the description that the auxiliary step is simple in construction and not liable to get out of order easily, since it is devoid of complicated parts, and that it may be applied to existing cars without any extensive changes in the cars being necessary.

I claim:

1. The combination with the car body and the fixed steps thereof, of an auxiliary step below the fixed steps, a bar secured to each end of the said step, bearings on the side plates of the fixed steps in which the bars are 85 slidable, said bars having angular upper ends for limiting their movement in the bearings, a rock shaft journaled between the side plates and provided at one end with a crank and at its center with a rigid arm, a link connecting the arm with the auxiliary step, a link pivoted to the crank and 90 slideable through the platform of the car, a lever pivoted on the car and connected with the upper end of the link, said link having an 95 integral collar, whose upper face is flat and the lower face beveled, and means through which the link is slideable for engagement by the collar to prevent the upward movement thereof, said means comprising a plate secured to the platform, a pair of levers pivoted thereto and movable toward and from each other, each of said levers having at one end a recessed jaw for receiving the link, and a spring acting to move the jaws 105 toward each other, one of said levers having its opposite end extended, for the purpose set forth.

2. The combination with the car body and the fixed steps thereof, of an auxiliary step below the fixed steps, a bar secured to each end of the said step, bearings on the side plates of the fixed steps in which the bars are 110 slidable, said bars having angular upper ends for limiting their movement in the bearings, a rock shaft journaled between the side plates and provided at one end with a crank and at its center with a rigid arm, a link connecting the arm with the auxiliary step, a link pivoted to the crank and slideable through the platform of the car, a lever pivoted on the car and connected with the upper end of the link, said link having an 115 integral collar, whose upper face is flat and the lower face beveled, and means through which the link is slideable for engagement by the collar to prevent the upward movement thereof, said means comprising a pair of levers, each having at one end a recessed 120 jaw for receiving the link, a spring pressing 125

the jaws together, and means for moving the levers apart.

3. The combination with the car body and the fixed steps thereof, of an auxiliary step 5 below the fixed steps, a bar secured to each end of the said step, bearings on the side plates of the fixed steps in which the bars are slidable, said bars having angular upper ends for limiting their movement in the 10 bearings, a rock shaft journaled between the side plates and provided at one end with a crank and at its center with a rigid arm, a link connecting the arm with the auxiliary step, a link pivoted to the crank and slidable 15 through the platform of the car, a lever pivoted on the car and connected with the upper end of the link, said link having an integral collar, whose upper face is flat and the lower face beveled, and means, through 20 which the link is slidable for engagement by the collar to prevent the upward movement thereof, said means comprising a pair of recessed jaws through which the link is slidable, a spring pressing the jaws together, 25 and means for releasing the jaws.

4. The combination with the car body and the fixed steps thereof, of an auxiliary step below the fixed steps, a bar secured to each end of the said step, bearings on the side 30 plates of the fixed steps in which the bars are slidable, said bars having angular upper ends for limiting their movement in the bearings, a rock shaft journaled between the side plates and provided at one end with a 35 crank and at its center with a rigid arm, a link connecting the arm with the auxiliary step, a link pivoted to the crank and slidable through the platform of the car, a lever pivoted on the car and connected with the 40 upper end of the link, said link having an integral collar, whose upper face is flat and the lower face beveled, and means through which the link is slidable for engagement by the collar to prevent the upward movement 45 thereof.

5. The combination with the car body and the fixed steps thereof, of an auxiliary step below the fixed steps, a sliding connection between the auxiliary step and the fixed 50 steps, means for limiting the outward movement of the auxiliary step, a rock shaft journaled between the side plates and provided at one end with a crank and at its center with a rigid arm, a link connecting the arm 55 with the auxiliary step, a link pivoted to the crank and slidable through the platform of the car, a lever pivoted on the car and connected with the upper end of the link, said link having an integral collar, whose upper 60 face is flat and the lower face beveled, and means through which the link is slidable for engagement by the collar to prevent the upward movement thereof.

6. The combination with the car body and

the fixed steps thereof, of an auxiliary step 65 below the fixed steps, a sliding connection between the auxiliary step and the fixed steps, means for limiting the outward movement of the auxiliary step, a rock shaft journaled on the fixed steps and provided at one 70 end with a crank and at its center with a rigid arm, a connection between the arm and the auxiliary step, a link connected to the crank arm and slidable through the platform, means on the car body and connected 75 with the link for moving the same vertically, and means through which the link is slidable for retaining it in lowered position, said means comprising spring pressed recessed jaws for receiving the link, said link having 80 a collar with a flat upper face and a beveled lower face for engagement by the jaws, and means for separating the jaws.

7. The combination with the car body and the fixed steps thereof, of an auxiliary step 85 below the fixed steps, a sliding connection between the auxiliary step and the fixed steps, means for limiting the outward movement of the auxiliary step, a rock shaft journaled on the fixed steps and provided at one 90 end with a crank and at its center with a rigid arm, a connection between the arm and the auxiliary step, a link connected to the crank arm and slidable through the platform, means on the car body and connected 95 with the link for moving the same vertically, and means through which the link is slidable for retaining it in lowered position, said means comprising spring pressed recessed jaws for receiving the link, said link 100 having a collar with a flat upper face and a beveled lower face for engagement by the jaws.

8. In a device of the class described, an auxiliary step, a longitudinally movable link 105 connected therewith for moving the step, a pair of spring pressed recessed jaws through which the link slides, said link having a collar whose one face is inclined and the other flat, for the purpose set forth.

9. In a device of the class described, an auxiliary step, a longitudinally movable link connected therewith for moving the step, a pair of spring pressed jaws between which the link slides, said link having a collar whose lower face is inclined and the other flat for the purpose specified.

10. In a device of the class described, an auxiliary step, a longitudinally movable link connected therewith for moving the step, a 120 pair of spring pressed gripping jaws through which the link slides, and means in connection with one of the jaws for moving them apart.

WILLIAM OLIVER DALY.
